SHIRT CONSTRUCTION

Max D. Taylor, Jackson, Mich.

Application February 1, 1947, Serial No. 725,895

6 Claims. (Cl. 2—115)

1

This invention relates to shirts and more particularly to improvements in shirts of the slip-over type which are at present on the market.

I believe that my shirt construction can be adapted to replace present shirt constructions of all of the various types. Shirts have been in the past provided with various kinds of openings to permit their being put on and taken off, such as the shirt which is open completely down the front, the shirt which is open at the collar and for a short distance down the front and is provided with various types of devices to hold it in a closed condition, the shirt which is open down the back, the shirt which has a button closure along one shoulder seam, around the front of the sleeve seam and down the side, and the shirt which is constructed with an overlapping or fold-over front which provides two pieces of cloth which cover the chest of the wearer. All of these shirt constructions are fairly expensive to make, since they are time-consuming in the manufacturing process, and none of them is totally satisfactory to the wearer, either from the standpoint of convenience in getting into them or of appearance when worn. There is, in fact, a noticeable trend to eliminate the fancy work on the front of men's shirts, as may be seen by comparing the front facing as presently used on shirts with the more complicated front fly arrangement of fifteen years ago. It is with this thought in mind that I have constructed my new type shirt which is of the slip-over type and embodies a perfectly plain front panel along with a simple neat-appearing closure which is easy to manufacture and is convenient to the wearer.

It is an object of this invention to provide a shirt construction which omits the conventional front, back or shoulder openings and which substitutes therefor a simplified closure.

Another object is to provide a shirt with openings in novel positions in the shoulder yokes which, by the nature of the openings, eliminates the necessity of rows of buttons or other closing devices in the yokes, which older types of construction, in spite of the most careful work in their manufacture, are usually prone to have excess material which gathers and bunches, thereby producing a closure which is anything but neat.

A further object of this invention is to provide a shirt construction easily adapted to any type of shirt. I believe that my shirt construction will find immediate favor in the field of sport shirts, but it is readily adaptable to the

2

usual business shirt, work shirt, and hunting shirt. It is also easily adaptable for use in the construction of dress shirts of the stiff front type, which type of shirt has always been a problem due to the fact that the front must be impeccably neat while still feeling comfortable to the wearer.

Other objects and advantages of my shirt construction will appear from a consideration of the following specification when considered in connection with the appended claims and accompanying drawings, in which

Fig. I is a view in perspective of a shirt constructed according to my invention,

Fig. II is a view in elevation of the back of such a shirt,

Fig. III is a view of the front of the shirt with the shoulder flaps in the closed position,

Fig. IV is a view of the front panel of the shirt,

Fig. V is a view of the back panel of the shirt,

Fig. VI is a view of an alternative back panel, constructed with a back yoke and pleats,

Fig. VII is a view of the collar which is used on my shirt prior to its being sewed onto the back panel, and

Fig. VIII is a view of the facing which is sewed to the top of the front panel, and which holds the front panel up against the collar.

In the drawings, the shirt 10 is provided with any kind of sleeves 12 and 14, which are joined to the shirt body at seams 16 and 18, and with the usual rolled down attached collar 20, provided with a tapered collar band 22 for attachment to the shirt 10. The back panel 24 is cut as shown in Fig. V, with edges 26 and 28 to form the side seams, curved edges 30 and 32 to join with sleeves 12 and 14 in shoulder seams 16 and 18, edges 34 and 36 which are faced and not sewed to another part, and curved edge 38 which is sewed to collar band 22 at seam 40. From a consideration of Fig. I, it can be seen that curved edge 38 does not extend completely around collar band 22, but that it does join roughly one half of collar band 22, the center of the back of collar band 22 being joined to the center of the curve of edge 38. This leaves the front portion of collar band 22 free of attachment. It is also apparent from Figs. I and III that edges 34 and 36 of back panel 24 extend over the top of the shoulder and for a short distance down the front of the shirt.

Front panel 42 is cut with side edges 44 and 46 which join with edges 26 and 28 respectively of back panel 24 to form the side seams, curved edges 48 and 50 which join with sleeves 12 and

14 and curved edges 30 and 32 of back panel 24 in shoulder seams 16 and 18, thereby attaching the sleeves to the body of the shirt, edges 52 and 54 which are sewed to back panel 24 at seams 56 and 58, edges 60 and 62 which are faced and pass at an angle over the shoulders, and curved edge 64 which is completed by facing 66 and fits around the front of collar band 22 and under collar 20, to hold front panel 42 in place. It is apparent from Figs. I, II and III that the shoulder portions of front panel 42, as defined by edges 48, 52 and 60, and edges 50, 54 and 62, overlap the ends of back panel 24 and provide a smooth, one-piece front which has a tendency, by reason of the way it is cut, to hang smoothly and to feel comfortable, as well as providing a large opening through which the wearer's head may pass when putting on or taking off the shirt.

In order to provide means for holding the shirt in a closed condition, I suggest using a plurality of snap fasteners suitably positioned around collar band 22. I have found that four snap fasteners, positioned in the manner to be described, will hold the shirt closed, although I recognize that a greater or lesser number may be used. As may be seen in Figs. I, VII and VIII, I position two snap fasteners 68 and 70 adjacent the ends of collar band 22 to engage their counterpart snap fasteners 69 and 71 on front facing 66. This engagement will hold front panel 42 in engagement with collar band 22. I also place snap fasteners 72 and 74 on collar band 22 behind the junctures of edges 34 and 36 with collar band 22, to engage their counterpart snap fasteners 73 and 75 which are placed adjacent the outer ends of front facing 66. This engagement will hold edge 64 of front panel 42 smoothly against collar band 22, and will also hold edges 60 and 62 in close contact with back panel 24 as edges 60 and 62 extend over the shoulder.

Most sport shirts today are constructed with pleated backs, which construction is entirely possible with my shirt. I have shown, in Fig. VI, an alternative back panel 24', the lower portion of which is constructed with the general outline of back panel 24, with edges 26' and 28' cut to join with edges 44 and 46 of front panel 42 to form the side seams. Alternate back panel 24' is different from back panel 24 in that it is constructed with a shoulder yoke 76 which joins back panel 24' at seam 78. This separable yoke construction allows the insertion of additional fullness in back panel 24', thereby giving the extra material and seam structure necessary for pleats 30. In other regards, back panel 24' with shoulder yoke 76 joined thereto, is similar to back panel 24, in that it has curved edges 30' and 32' to join with sleeves 12 and 14, in shoulder seams 16 and 18, edges 34' and 36' which are faced and not sewed to another part, and curved edge 38' which is sewed to collar band 22 at seam 40.

In order to put on a shirt constructed according to my invention, the snap fasteners 68, 70, 72 and 74 are unsnapped, the wearer inserts his arms and head through the open bottom of the shirt, as if getting into a pull-over sweater, and pulls the shirt down over his body, threading his arms into the sleeves. The process is completed by closing the snap fasteners. This provides a shirt with the objects and advantages set forth above.

Having thus described my invention, what I claim as new and desire to protect by Letters Patent is:

1. A garment comprising back and front pan-

els, a collar joined to said panels, said back panel having extensions which extend over the front of the shoulders of the shirt and having a neck portion which is permanently attached to said collar for a distance less than the total perimeter of said collar, said front panel having extensions which overlap the extensions of said back panel and having a neck portion which is detachably attached to said collar for a distance less than the total perimeter of said collar but more than the difference between the distance of attachment of said back panel and the total perimeter of said collar, the extensions of said back and front panels overlapping in lines converging in a point beyond their respective junctures with said collar.

2. A garment comprising a back panel presenting at its upper end a curved neck recess and a pair of shoulder extensions, a front panel presenting at its upper end a curved neck recess and a pair of shoulder extensions, a collar band permanently attached for part of its perimeter to the curved neck recess of said back panel, a collar permanently attached to said collarband, means for detachably connecting the curved neck recess of said front panel to part of the perimeter of said collar band, shoulder seams attaching said back and front panels so that the shoulder extensions of said front panels overlap the shoulder extensions of said back panels.

3. A garment comprising a back panel presenting at its upper end a curved recess and extending shoulder portions, a front panel presenting at its upper end a curved recess and extending shoulder portions, a collar band, having an attached roll collar, permanently connected by a portion of its perimeter and throughout the curved recess to said back portion, means located at spaced intervals on said collar band and said front panel for detachably attaching the curved recess of said front panel to a portion of the perimeter of said collarband, and shoulder seams fastening the extending shoulder portions on said front panel in overlapping relationship with the extending shoulder portions on said back panels.

4. In a garment, a back panel, a pair of extending shoulder portions at the upper end of said back panel, a curved recess positioned between said shoulder portions, a collar permanently connected through a portion of its perimeter to said curved neck portion, a front panel, a second pair of extending shoulder portions at the upper end of said front panel, a second curved recess defined between said second extending shoulder portions, means located at spaced intervals for detachably attaching said second curved recess to a portion of the perimeter of said collar, and seams positioning said extending shoulder portions of said front panel in overlapping relationship to said extending shoulder portions of said back panel.

5. A garment comprising a back panel presenting at its upper end a curved recess and extending shoulder portions, a front panel presenting at its upper end a curved recess and extending shoulder portions, a collar band permanently attached by a portion of its length to the curved recess in said back panel, means located at spaced intervals on said collar band and said front panel for detachably attaching the curved recess of said front panel to a portion of the length of said collar band, and a plurality of seams attaching said back panel to said front panel such that the extending shoulder portions

of one of said panels overlap the extending shoulder portions of the other of said panels.

6. A garment comprising a back panel, a yoke portion attached to said back panel presenting a pair of extending shoulder portions and defining a curved neck recess therebetween, a collar band attached through part of its length to the curved neck recess of said yoke portion, a front panel presenting a pair of extending shoulder portions and defining a curved neck recess therebetween, and attachment means positioned on said collar band and said front panel whereby the curved neck recess of said front panel may

be retained in close proximity to part of the length of said collar band.
